UNITED STATES PATENT OFFICE

2,332,770

LIGHTING FIXTURE

David W. Abernathy, Chicago, Ill., assignor to Products Development, Inc., Chicago, Ill., a corporation of Illinois

Application April 1, 1942, Serial No. 437,130

4 Claims. (Cl. 240—78)

This invention relates to lighting fixtures, and more particularly to a lighting fixture for use with tubular lighting means, such as for example, fluorescent gaseous discharge tubes.

An object of this invention is to provide a novel and improved construction for a lighting fixture.

A further object of this invention is to provide a novel and improved fixture of the character described, which will be light, yet very sturdy and resistant to either longitudinal or transverse bending.

A further object of the invention is to provide a fixture of the character described which will be simple and economical in construction.

A further object of this invention is to provide a fixture of the character described which will enable the space above the fixture to be illuminated at no expense of the usual illumination.

Still a further object of the invention is to provide a fixture of the character described wherein the various elements of the circuit will at all times be easily accessible for service and inspection.

Other objects lie in the specific constructional details of the fixture whereby same may be easily fabricated and assembled.

With the foregoing and other objects in view which will appear as the description proceeds, the invention consists of certain novel features of constructions, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a perspective view of a lighting fixture embodying my invention.

Fig. 2 is a sectional view taken through the

fixture on the line 2—2 of Fig. 1 in the general direction indicated.

Fig. 3 is a fragmentary top plan view of an end of the fixture.

Referring now to the specific details of my fixture, reference character 10 designates generally a reflector formed of sheet metal and adapted to be suspended from the ceiling for example in order to throw light downwardly. The reflector 10 has curved sides 11 each terminating in an upturned flange 12 which serves to provide longitudinal rigidity for the curved portions 11, and also to prevent deformation of the edges of the reflector. The curved portions 11 are connected across the top of the reflector 10 by a planar portion 13, the central part of which is downwardly offset to form a channel or well 14 extending longitudinally of the entire fixture.

The reflector is adapted to downwardly direct illumination emanating from two tubular lamps 15 which are arranged longitudinally of the fixture and are disposed immediately below the planar portion 13 where same have not been downwardly off-set. The lamps 15 are preferably gaseous discharge devices, having the walls thereof treated to produce the well-known fluorescent illumination. The ends of the lamps 15 are engaged by conventional electrical socket devices 16 which are fixed adjacent the ends of the reflector 10. Obviously, the reflector has appropriate openings for the accommodation of said devices 16. The drawing diagrammatically illustrates a thermostatic starting switch 17, which is provided for each tube and installed adjacent the socket devices at the ends of the reflector.

The illumination from the fluorescent lamps 15 is directed downwards by the deflector, as previously explained; hence that portion which radiates upwards will normally be reflected back into the tubes 15. A series of elongated openings 18 along the portions 13 disposed directly above the tubes 15 throughout the length of the reflector 10 are provided in my improved construction. In this manner light from the tubes 15 which would normally be lost is directed upwards and serves to illuminate the otherwise dark space above the fixture.

Obvious advantages of this type of fixture are that the added illumination is achieved without the use of any extra tubes or other equipment. In commercial establishments illumination of the type afforded by my invention is of prime importance. In industrial establishments many advantages accrue from increased illumination of

the portion of the ceiling directly above the fixture.

About each of the openings 18 is provided an upstanding flange 19. The flanges 19 serve the purpose of strengthening the reflector 10 at its weakest points, namely in the planar portions 13 between the curved portions 11 and the well or channel 14. The transverse portions of the flanges 19 oppose transverse bending, and the longitudinal portions of the flanges 19 rigidify the reflector 10 longitudinally thereof. In fabrication, the openings 18 and the flanges 19 may be formed by one continuous follow-through operation, which consecutively punches out the centers and draws the flanges 19.

My invention is not limited to this manner of formation of the flanges, nor is it essential that they be integrally formed with the reflector 10. Prefabricated flanges 19 welded in place will serve to strengthen my fixture in a like manner.

Since the central well 14 extends the entire length of the reflector 10, it also serves to rigidify the fixture against longitudinal bending or twisting. The channel 14 also serves another purpose. Such wires as are necessary for the circuit of the lamps 15 are safely and conveniently disposed within the trough formed by the channel 14 as shown at 20. Centrally of the fixture, the usual ballast elements are installed in the well 14. They are covered and enclosed by means of a removable sheet metal cover member 21 which overlies the central portion of the well 14.

Adjacent the ends of the fixture are provided enclosing means for the socket devices 16 and the various connections necessary therefor. I prefer a box-like arrangement having a removable cover whereby access may be quickly had to the connections. As shown in the drawing, I provide a U-shaped sheet metal member 22, having a portion 23 extending transversely of the reflector 10 and across the well 14, and having side portions 24 extending parallel to the well 14. The member 22 is rigidly attached to the reflector 10 by welding the flanges 25 bent therefrom to the planar portions 13 as shown. The cover member 26 covers the open top and front of the space enclosed by the member 22. The member 26 is also formed of sheet metal and comprises a top portion 27, and a front portion 28 the lower edge of which has contours enabling same to snugly fit the top of the reflector 10 and the well 14. Side flanges 29 facilitate easy installation. The cover member 26 is adapted to be snapped on to the member 22 and fastened in place by screws 30 which enter lugs 31 integrally formed with the member 22.

In order to cover the well 14 and protect the same, I have provided sheet metal plates 32 which overlie the well and have their edges secured by spot welding or in some other suitable manner to the planar portions 13. These cover plates 32 also aid in eliminating both transverse and longitudinal bending, and hence foreclose any possibility of the fixture twisting or becoming deformed. I provide two of such plates 32, one between each member 22 and the end of the central cover member 21. Each end of each plate member 32 has an upwardly bent flange 33. The flange 33 at the outer edge of the plate members engages under the bottom edge of the portion 23 of the member 22 and is spot-welded thereto, while the flanges 33 at the center of the fixture serve as means whereby the cover member 21 may

be firmly held in position by snapping in place over the same.

The wall 23 has an upwardly extending portion 34 provided with openings 35 and serving as a bracket whereby the entire fixture may be suspended from a ceiling. Other means of installation of the fixture or support thereof may, of course, be utilized.

It will be seen that I have provided a fixture 10 which is light, but which is at the same time rigid and practically free from bending and twisting. All manner of bending stress has been practically eliminated without the use of superfluous bracing. Further, the fixture is capable of economical fabrication in large quantities. I have also, by means of my fixture, provided greater and more complete illumination than is possible with conventional fixtures using the same electrical and illuminating equipment.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. A fixture for use in connection with fluorescent illuminating means, comprising a substantially elongated sheet metal reflector member, socket devices affixed to the ends of the reflector and adapted to retain said illuminating means in position, ballast means for aiding in the operating of said fluorescent illuminating means, said reflector member having a U-shaped central channel formed therein along the whole length of the reflector member, said socket devices and ballast means being disposed within said U-shaped channel, protective cover means overlying the ends of the channel and enclosing the socket devices at opposite ends of the fixture, said cover means comprising transverse parts snugly fitting the profile of said U-shaped channel, and separate cover means overlying the center of said channel and protectively enclosing said ballast means.

2. A fixture for use in connection with fluorescent illuminating means, comprising a substantially elongated sheet metal reflector member, socket devices affixed to the ends of the reflector and adapted to retain said illuminating means in position, ballast means for aiding in the operating of said fluorescent illuminating means, said reflector member having a U-shaped central channel formed therein along the whole length of the reflector member, said socket devices and ballast means being disposed within said U-shaped channel, protective cover means overlying the ends of the channel and enclosing the socket devices at opposite ends of the fixture, said cover means comprising transverse parts snugly fitting the profile of said U-shaped channel, separate cover means overlying the center of said channel and protectively enclosing said ballast means, and plate members fixedly secured to the top of said reflector member, overlying said channel and closing those portions of said channel extending between said end protective cover means and the center protective cover means, each of said cover means being separately re-

movable whereby access may be had to said socket devices or ballast means.

3. A fixture for use in connection with fluorescent illuminating means, comprising a substantially elongated sheet metal reflector member, socket devices affixed to the ends of the reflector and adapted to retain said illuminating means in position, ballast means for aiding in the operating of said fluorescent illuminating means, said reflector member having a U-shaped central channel formed therein along the whole length of the reflector member, said socket devices and ballast means being disposed within said U-shaped channel, protective cover means overlying the ends of the channel and enclosing the socket devices at opposite ends of the fixture, separate cover means overlying the center of said channel and protectively enclosing said ballast means, plate members fixedly secured to the top of said reflector member, overlying said channel and closing those portions of said channel extending between said end protective cover means and the center protective cover means, each of said cover means being separately removable whereby access may be had to said socket devices or ballast means, and a plurality of elongated light-transmitting parts provided in said reflector directly above and along each of said illuminating means, each of said ports having upstanding flanges surrounding same.

4. A fixture for use in connection with fluores-

cent illuminating means, comprising a substantially elongated sheet metal reflector member, socket devices affixed to the ends of the reflector and adapted to retain said illuminating means in position, ballast means for aiding in the operating of said fluorescent illuminating means, said reflector member having a U-shaped central channel formed therein along the whole length of the reflector member, said socket devices and ballast means being disposed within said U-shaped channel, protective cover means overlying the ends of the channel and enclosing the socket devices at opposite ends of the fixture, said cover means comprising transverse parts snugly fitting the profile of said U-shaped channel, separate cover means overlying the center of said channel and protectively enclosing said ballast means, plate members fixedly secured to the top of said reflector member, overlying said channel and closing those portions of said channel extending between said end protective cover means and the center protective cover means, each of said cover means being separately removable whereby access may be had to said socket devices or ballast means, and a plurality of elongated light-transmitting ports provided in said reflector directly above and along each of said illuminating means, each of said ports having upstanding flanges surrounding same.
